UNITED STATES PATENT OFFICE.

ANTHONIUS M. VAN DOORN, OF NEWTON, MASSACHUSETTS, ASSIGNOR, BY MESNE ASSIGNMENTS, TO AMERICAN THERMOPHONE COMPANY, OF BOSTON, MASSACHUSETTS, A CORPORATION OF MASSACHUSETTS.

MACHINE FOR FINISHING THERMOPHONES.

1,338,887.

Specification of Letters Patent.

Patented May 4, 1920.

Application filed March 1, 1919. Serial No. 280,168.

To all whom it may concern:

Be it known that I, ANTHONIUS M. VAN DOORN, of Utrecht, Holland, a subject of Wilhelmina, Queen of the Netherlands, residing in Newton, Massachusetts, have invented a new and useful Improvement in Machines for Finishing Thermophones, of which the following is a specification.

In an application for United States Letters Patent filed contemporaneously herewith, Serial No. 280,167, I have described a machine for making what may be called a thermophone blank, that is to say, a partially constructed thermophone, my present invention relating to a machine for the completion of the thermophone. As stated in my companion application, the completed article is a device approximately half an inch in diameter and three eighths of an inch high (see Figure 12) and contains a series of looped conductors arranged electrically in parallel comprising Wollaston wires which at their base are ten microns in diameter and where the metal coating has been etched therefrom 2 microns in diameter. The constructing of the thermophone must be conducted with great care to avoid breakage, and at the same time the construction should be such that the electrical resistance of each loop shall be slightly over an ohm and where, as shown in the drawings, there are 18 loops arranged in parallel the total resistance of the device shall be approximately 22 ohms.

For the make-up of a blank, wires approximately $7\frac{1}{2}$ mm. in length are used and in the final operation of finishing the thermophone a length of $5\frac{1}{2}$ mm. is etched from its middle, leaving a corresponding length of its core of preferably platinum wire exposed to furnish the heater. The whole device, therefore, is one of such size and delicacy that it is very difficult to construct, otherwise than by the most careful manipulation or the most accurate machinery.

My present invention will be understood by reference to the drawings in which a machine for finishing the mechanical structure of the thermophone is shown in its preferred form and wherein

Fig. 1 is a side elevation, and

Fig. 2 a longitudinal section on line 2—2 of Fig. 3 of a machine embodying my invention.

Fig. 3 is a section on line 3—3 of Fig. 1, 55 and

Fig. 4 is a section on line 4—4 of Fig. 1.

Figs. 5, 7, 8 and 9 show the operation of the machine upon the blank.

Fig. 6 being a side elevation of one of 60 the tools.

Fig. 10 shows the blank in form to be made up by the machine.

Fig. 11 is a side elevation of the blank after it has been finished by the machine, 65 and

Fig. 12 shows a longitudinal section of the finished thermophone and its cover.

Referring to Figs. 1 to 4, inclusive, A is a base or table which is slotted as at a 70 and has on its upper surface tracks A^1 . A work holder B is mounted on the tracks A^1 and is clamped in position by a screw b . It has two uprights carrying bushings b^1 75 constructed preferably with ball bearings b^2 , b^3 in which is mounted a sleeve C in such a manner that the sleeve may be revolved. For this purpose the sleeve C carries at its rear end a pulley D. Within the sleeve C is a spindle E which is reduced 80 at one end as at e to a shape to assist in the loop-forming operation below described and is still further reduced to provide a threaded end or screw e^1 to receive a nut to hold the work in place. The spindle is 85 also grooved as at e^2 to receive a screw e^3 which passes through the sleeve C, to cause the rotation of the spindle with the rotation of the sleeve and at the same time to allow the spindle to have a longitudinal movement with relation to the sleeve. 90

The spindle at its outer end carries a knurled handle E^1 and also a cross-arm E^2 of suitable shape to engage shouldered pins d , d^1 projecting rearwardly from the pulley D. By means of the handle the spindle may be moved longitudinally and by means of the shoulders on the pins d , d^1 and cross-arm E^2 the spindle is locked forward or 95 back and power is transferred from the pulley to rotate it.

The construction of these parts is such that the application of power by means of a suitable belt on the pulley D will rotate both the sleeve and the spindle at all times, 105 but at any moment the spindle may be moved longitudinally in such a way that its end will project from the sleeve as shown.

in Figs. 1, 2, 5, 8 and 9, or may be retracted as shown in Fig. 7.

On the rails A¹ is also mounted a sliding support F for a tool rest F¹. On the sliding support F is mounted a cross slide F². The cross slide F² has a hub F³ having a socket in which sets a stud f forming the lower portion of the tool rest F¹. f¹ is a strap which surrounds a split sleeve f² forming an upward extension of the hub F³ as well as the stud f, and f³ is a screw which passes through the ends of the strap f¹ and is operated by a handle f⁴ so as to clamp the strap around the sleeve f² and stud f and so clamp the tool holder in place.

G is a screw which passes up through the slot a in the base A and screws into a dovetail nut G¹ which is mounted on the upper side of the slide F and in a dovetail groove 20 in the cross slide F² so that upon tightening the screw G the parts are clamped together in place on the rails. When the screw G is loosened the cross slide F² may be adjusted crosswise of the machine and also may be 25 turned at an angle to the spindle if desired. When proper adjustment has been reached the tightening of the screw G will hold the parts in proper position. A slight adjustment of the angle of the tool rest to the 30 spindle may be had by loosening the handle f⁴.

It will be noted that the blank to be formed into a thermophone on this machine comprises a core 1 surrounded by a clamping piece or a thimble 2 crimped in to the form of the periphery of the core, and a plurality of wires 3 projecting straight outwardly therefrom, all of the same length (see Fig. 10 where the blank is shown in side 35 elevation and Fig. 5 where these parts may be identified). In this form it comes from the machine first above referred to. The operation to be carried out by this machine is the bending of the wires into loops (see 40 Fig. 11) and the fastening of their free ends after they have been so bent to a metallic part which may form an electrode.

For this purpose the spindle E is pushed 45 forward (see Figs. 1, 2, 5, 8 and 9) and there is first placed upon the threaded end e¹ of it the blank shown in Fig. 10, the interior of the core 1 being preferably threaded for this purpose as shown in Fig. 12. This gives the wires 3 their initial bend (see Fig. 5). 50 There is next placed upon the threaded portion e¹ of the spindle a former H, that is, a cylindrical metal piece closed at one end except for a threaded opening to enable it to be screwed onto the screw e¹, its cylindrical 55 part being of sufficient length and properly shaped to allow the wires 3 to be bent over its outer edge. It also has a shoulder h against which the ends of the loops are bent (see Fig. 7). There is then preferably placed 60 upon the same screw e¹ a spacer J, which is

shaped to fit over the former H, but has deep serrations j providing points j¹ the purpose of which is to enter between the various wires 3 and so arrange and space them before they are finally bent as to prevent their 70 being entangled during the forming operation. A nut e⁴ is then screwed to the threaded portion e¹ to give the wires a preliminary bending by forcing them against the shoulder e⁵ (see Fig. 5 in which the wires are 75 shown engaging the shoulder e⁵ and bent outwardly thereby). The spacer J is then removed and the nut replaced and the spindle E is then drawn within the sleeve C so that this end of the sleeve C and the former 80 H will coöperate to double back the wires 3 (see Fig. 7).

K is a split ring which is carried by the sleeve C and is placed on the sleeve before the blank is put in place, and when the 85 spacer has been removed this ring is slipped off the sleeve and in front of it so that it will engage the wires and iron them against the former H. The former is then removed and a properly shaped piece of bakelite or the 90 like insulator 4 is placed around the core 1 and forced between the thimble 2 and the ring K which holds the wires in position, thus insulating the electrodes from each other. The nut e⁴ is then removed and the 95 thimble 5 is then placed over the blank, the nut e⁴ being replaced and screwed up to force the parts into final position and the ends 6 of the loops about the ring K (see Fig. 8). The thimble 5 is then crimped or 100 spun by a hand tool of proper shape resting on the tool rest F¹ into engagement with the periphery of the insulator and also around the ring K, thus attaching the loops firmly 105 to the ring (see Fig. 9). The thermophone 110 is then finished except for the addition thereto of the cover member 7 which fits down over, and may be attached to, the base of the thermophone in any desired way, forming a resonance chamber the walls of 115 which coöperate with the compressional waves caused by the changes in temperature in the loops. Before this cover 7 is put on, however, it is necessary that the loops shall 120 be etched by means of any suitable acid to remove a portion of the coating of the Wolaston wire, this being done by dipping the tips of the loops into the acid for a predetermined length. It is necessary that this be done accurately in order that a standard of 125 resistance in thermophones may be maintained and also so that the resistance of each loop shall be substantially the same as that of every other loop, this forming a part of a contemporaneous application.

While my invention may be otherwise embodied, the above described is a simple and convenient means for accomplishing the desired result. The hand tool referred to is not shown, as it may be of any convenient 130

shape depending upon the work to be done, as will be understood by any lathe worker.

What I claim as my invention is:—

1. A machine of the kind described comprising a longitudinally movable spindle, a sleeve located about said spindle, said spindle and said sleeve being connected whereby they will rotate together, said spindle being provided at one end with means to attach a blank thereto, and having a means located near said end whereby wires projecting from said blank may be deflected outwardly in the act of attaching said blank to said spindle.
2. A machine of the kind described comprising a longitudinally movable spindle, a sleeve located about said spindle, said spindle and said sleeve being connected whereby they will rotate together, said spindle being provided at one end with means to attach a blank thereto, and having a means located near said end whereby wires projecting from said blank may be deflected outwardly in the act of attaching said blank to said spindle, in combination with a forming means located to engage said wires laterally as they are deflected and determine their point of deflection.
3. A machine of the kind described comprising a longitudinally movable spindle, a sleeve located about said spindle, said spindle and said sleeve being connected whereby they will rotate together, said spindle being provided at one end with means to attach a blank thereto, and having a means located near said end whereby wires projecting from said blank may be deflected outwardly in the act of attaching said blank to said spindle, in combination with a forming means located to engage said wires laterally as they are deflected and determine their point of deflection, and means to enter between adjacent wires to prevent them from interengaging.
4. A machine of the kind described comprising a longitudinally movable spindle, a sleeve located about said spindle, said spin-

dle and said sleeve being connected whereby they will rotate together, said spindle being provided at one end with means to attach a blank thereto, and having a means located near said end whereby wires projecting from said blank may be deflected outwardly in the act of attaching said blank to said spindle, in combination with a forming means located to engage said wires laterally as they are deflected and determine their point of deflection, the end of said sleeve being shaped whereby it may bind said deflected wires over said forming means when said spindle is retracted.

5. A machine of the kind described comprising a longitudinally movable spindle, a sleeve located about said spindle, said spindle and said sleeve being connected whereby they will rotate together, said spindle being provided at one end with means to attach a blank thereto, and having a means located near said end whereby wires projecting from said blank may be deflected outwardly in the act of attaching said blank to said spindle, in combination with a forming means located to engage said wires laterally as they are deflected and determine their point of deflection, said forming means being of less diameter than the interior of said sleeve whereby when the spindle is retracted said forming means will be drawn within said sleeve and the deflected wires will thereby be bent down over the forming means.

6. In a machine of the kind described, a longitudinally movable spindle, a sleeve surrounding said spindle rotatable therewith, a yielding ring carried by said sleeve, said spindle being adapted to carry a blank having wires projecting therefrom, means for deflecting said wires, and means whereby said ring when pushed off said sleeve will cause said wires to be doubled, and means whereby the ends of said wires will be bent around said ring.

ANTHONIUS M. VAN DOORN.
